UNITED STATES PATENT OFFICE.

CHARLES E. STERNE, OF SAN DIEGO, CALIFORNIA, ASSIGNOR TO
STERNE BROS. CO., OF SAN DIEGO, CALIFORNIA, A CORPORA-
TION OF CALIFORNIA.

SPEED-GOVERNOR.

SPECIFICATION forming part of Letters Patent No. 723,417, dated March 24, 1903.

Application filed May 2, 1901. Serial No. 58,529. (No model.)

To all whom it may concern:

Be it known that I, CHARLES E. STERNE, a citizen of the United States, residing at San Diego, in the county of San Diego and State 5 of California, have invented new and useful Improvements in Speed-Governors, of which the following is a specification.

Some of the objects of this invention are compactness, simplicity, and cheapness.

10 Another object of this invention is ease of manufacturing, assembling, and placing the governor in position on the engine.

The accompanying drawings illustrate my invention.

15 Figure I is an elevation of my newly-invented governor in position on an engine, a fragment of which is shown. The governor slide-valve of the engine, which is to be connected with the governor, is omitted from 20 this view. Fig. II is a vertical section of the same on line II II, Fig. III, looking in the direction of the arrow. This view is from the right of Fig. I, excepting that the governor-weights are turned a quarter-turn from the 25 position shown in Fig. I. The post or wrist-pin of the governor slide-valve of the engine is shown in section. Fig. IV is a plan of the 30 governor. A fragment of the slide-valve connection is shown. Fig. IV is a detail on a larger scale illustrating the tension device of the governor-weight spring.

35 1 indicates the rotary spindle. 2 indicates a sliding sleeve to rotate with said spindle.

3 indicates a spline between the shaft and 40 collar.

4 indicates sleeve-operating levers fulcrumed to the spindle by pins 5 and respectively weighted at one arm, as indicated by the balls 6.

45 7 indicates yielding means for drawing the weights 6 of the levers toward the axis of rotation. Such means may be of any suitable form, but preferably consists of a coil-spring, as shown in the drawings. The upper end of the spindle is preferably grooved circumferentially for the reception of the weighted portions of the levers or balls 6. The portion of the spindle above the groove can be turned or finished in any artistic manner, as shown 50 in the drawings.

8 indicates the regulator-operating means connected with the sleeve, to be operated thereby. Such means in the form of engine shown preferably consists in a bent lever, one end of which is forked, as shown at 9, to 55 removably fit upon the post or wrist-pin 10 of the slide-valve 11. The upper end of the sleeve 2 rests against a shoulder formed upon the spindle below the pivots 5.

12 indicates yielding means for holding the 60 sleeve against the shoulder and normally out of contact with but in the path of the sleeve-operating arms 13 of said levers 4.

By providing a shoulder 25 upon the spindle, whereby the sleeve is normally held out 65 of contact with the short arms of the weighted levers, a finer adjustment of the governor is secured, as the spring 7 can be made of only sufficient strength to return the balls to their normal position after the engine has stopped, 70 and the main portion of the resistance to the outward movement of the balls can be taken up and borne by the spring 12, which may be made adjustable. By constructing the parts in this manner the machine to which the governor is applied may be run up to any desired speed before the outward movement of the weights will cause the shorter arms to come into contact with the sleeve and cause it to begin to move the controlling mechanism, 75 as the shut-off or throttle.

The means 7 for drawing the weights of the levers toward the axis of rotation is adjustable as to tension by means of screws 14, which screw through the weighted balls 6 85 and are furnished on their inner ends, respectively, with eyes 15, in which the ends of the coil-spring 7 are caught.

16 indicates a cylindrical nut seated in cylindrical seats 17, in which the nuts turn 90 freely. Said nuts are screwed into the screws 14, respectively, and preferably are each provided with a slot 18 for a screw-driver, by which the nuts can be turned. The inner ends of the nuts and their respective seats 95 in the sockets are preferably ratchet shape to prevent unscrewing.

19 indicates recesses in the balls 6 to avoid contact of the balls with the spring 7.

The yielding means 12 for holding the sleeve 100

in the path of the arms 13 of the levers is preferably adjustable, as indicated by the screw-threaded connecting-rod 20, which slides through the bracket 21 and is secured by the 5 nut 22.

The spindle 1 is grooved or slotted longitudinally, as indicated at 23, and the bent levers 4 are mounted in said grooves and fulcrumed at their angles in said groove by the 10 pins 5. The spring 7 preferably extends through the groove and is therefore out of the way and concealed from view. The spring is attached to the balls substantially in line with the centers thereof and at right angles 15 to the axes of pivots 5, so that the tension upon the balls and levers and the fulcrum-pins 5 is even and true.

In practice the spindle 1 is preferably made of a cylindrical steel shaft which is turned 20 throughout, the groove 23 and the spline-seat 24 being milled. The spindle is appropriately shouldered at *a* and *b* on opposite sides of the bearing *c* of the bracket 21, which supports the spindle. *d* indicates an antifriction-washer between the shoulder *b* and the bearing *c*. *e* indicates the pinion, fitted against the shoulder *a* and by which the spindle is driven. The end of the spindle is screw-threaded, and the pinion *e* is secured on the 25 lower end of the spindle by the nut *f*.

The portions of the spindle between the different shoulders are each cylindrical with each succeeding cylinder away from the slotted portion of a less diameter than the preceding one and the tip of the smaller cylinder adapted to receive a fastener. After the weighted levers have been secured in the upper ends of the spindle the parts may be assembled in operative position by passing 35 the lower end of the spindle through the sleeve and through the bearing and then securing the pinion upon the end beyond the bearing by means of the nut or other fastener. This renders the device cheap of construction, easy to assemble, and very sensitive 40 and efficient in its operation.

By controlling the weighted levers with one spring and the throttling mechanism with another and adjusting each spring independently of the other the governor can be set to not begin to operate the throttling mechanism until after the engine has attained any desired speed, and after that it can only move the same with the desired rate of speed 50 to which the throttle has been adjusted. This permits of the governor being applied to various kinds or styles of engine and adapting it to the different kinds or classes of work which the engine may be called upon 55 to perform.

What I claim, and desire to secure by Letters Patent of the United States, is—

1. A speed-governor comprising a rotary spindle; a sliding sleeve to rotate with said spindle; sleeve-operating levers fulcrumed to the spindle and respectively weighted at one arm; yielding means for drawing the weights 65

of the levers toward the axis of rotation; regulator-operating means connected with said sleeve to be operated thereby; and means 70 for holding said sleeve normally out of contact with but in the path of the sleeve-operating arms of said levers.

2. A speed-governor comprising a rotary spindle; a sliding sleeve to rotate with said 75 spindle; sleeve-operating levers fulcrumed to the spindle and respectively weighted at one arm; adjustable yielding means for drawing the weights of the levers toward the axis of rotation; a stop for limiting the movement of 80 the sleeve toward and normally holding it out of contact with said levers, and regulator-operating means connected with said sleeve to be operated thereby.

3. In a speed-governor, the combination of 85 the grooved rotating spindle; the weighted bent levers fulcrumed in said groove and furnished respectively with sockets and with openings for a tension-spring and its fastenings; nuts respectively seated in said sockets; 90 screws in said nuts; and a tension-spring through the groove between the weights and fastened to said screws.

4. In a speed-governor, the combination of 95 the grooved rotating spindle; the weighted bent levers fulcrumed in said groove and furnished respectively with sockets and with openings for a tension-spring and its fastenings; nuts respectively seated in said sockets; 100 screws in said nuts; and a tension-spring between the weights and fastened to said screws, the nuts being furnished with ratchet-teeth, substantially as set forth.

5. In a speed-governor, a rotary spindle provided with weighted levers, yielding mechanism connected with said levers to prevent their outward movement, yielding engine-controlling mechanism in position to be operated by, but normally out of, contact with 105 said levers, and means for adjusting each of said mechanisms independently of the other.

6. In a speed-governor, an exteriorly-shouldered rotary spindle, the upper portion of which is provided with weighted levers and the portions between the shoulders are each 115 cylindrical, each cylinder toward the lower end being of a less diameter than the one above it, a sleeve between the upper shoulders, in the path of, but normally out of contact with, the levers, a bearing between the 120 intermediate shoulders, a pinion removably secured below the lower shoulder, and engine-controlling mechanism connected with the sleeve.

7. In a speed-governor, a rotary spindle, 125 the upper portion of which is slotted longitudinally near its upper end and grooved circumferentially at the upper end of the slot, a pair of bent levers pivotally mounted in the lower portion of the slot, the upper end of 130 each lever being provided with a spherical weighted portion adapted to normally rest in the groove, a spring secured at its ends to said weights and passed loosely through said

slot, a support, and a sleeve on the spindle for engaging with and operating engine-controlling mechanism.

8. A new article of manufacture, an exteriorly-shouldered spindle for speed-governors, the portion of which adjacent to one end is slotted longitudinally and is exteriorly grooved at the outer end of the slot, and the portion adjacent to the other end of the slot 10 is perforated transversely, the portions of the spindle between the shoulders, and the last shoulder and one end each being cylindrical,

each cylinder away from the slotted portion being of a less diameter than the one preceding it, and the tip of the smallest cylinder 15 being adapted to receive a fastener.

In testimony whereof I have signed my name to this specification, in the presence of two subscribing witnesses, at Los Angeles, California, this 27th day of April, 1901.

CHARLES E. STERNE.
